UNITED STATES PATENT OFFICE

JAMES J. DOLAN, OF SANDWICH, ILLINOIS, ASSIGNOR TO SANDWICH MANUFACTURING CO., A CORPORATION OF ILLINOIS

ELEVATOR

Application filed August 21, 1926. Serial No. 130,751.

This invention relates to sectional elevators and more particularly to devices for elevating grain and the like.

One of the objects of the invention is the provision of new and improved means for connecting together the sections of an elevator.

Another object of the invention is the provision of new and improved means for bracing and strengthening the individual units of a sectional elevator.

A still further object of the invention is the provision of a new and improved elevator that is cheap to manufacture, easily assembled, light and rigid in construction, strong, durable and one that is composed of a minimum number of parts.

Other and further objects and advantages of the invention will appear from the following description taken in connection with the accompanying drawings in which

Fig. 1 is a plan view of a portion of the improved elevator construction;

Fig. 2 is a side elevation thereof; and

Fig. 3 is an end elevation of one of the elevator units showing the conveyor chain in section.

In the form of the device selected to illustrate one embodiment of the invention, the reference character 10 designates generally an elevator which comprises one or more units 11. These units are similar in construction and only one need be described. The elevator may be extended to the desired length by adding additional units thereto.

In elevators of this general description, it is common practice to make them of sections or units but great difficulty has heretofore been experienced in attempts to design an elevator that will be sufficiently rigid to prove satisfactory and at the same time be durable, and one that may be manufactured at a reasonable cost. The present invention contemplates a sectional elevator in which each section is simple in construction, and when the sections are assembled the structure will be extremely rigid.

As shown, each section comprises a trunk or elevator member 13 thru which the grain

for bracing and strengthening the structure and for returning the corn accidentally shelled from the cobs or ears, as is usual in such constructions.

The trunk member 13 is provided with a bottom wall 17 and side walls 18 and 19. Preferably the elevator or trunk member is made of sheet metal bent to U-shape in cross section.

The pan member is likewise of sheet metal bent or stamped to U-form and comprises a bottom wall 21 and side walls 22 and 23.

The trunk and pan members are held in spaced parallel relation by a plurality of spacer members. Any suitable number of these spacer members may be employed for each unit section. As shown, a spacer member 24 is provided at each end of each section and a similar spacer member 25 is arranged adjacent to the central portion of the unit.

Suitable means are provided for bracing each section and for connecting the sections together. The spacer members 24 and 25 are so constructed and arranged that they materially assist in bracing the sections as well as retaining the trunk and pan members in spaced relation. The spacer members 24 and 25 are formed from channel bars and have their web portions rigidly connected to said trunk and pan members respectively as by bolts or rivets, as clearly shown in Fig. 2. The flanges 26 and 27 of the channel bars 24 and 25 respectively extend outwardly from said trunk and pan members.

Suitable tension members are employed for forming a rigid truss for each elevator unit. As shown, rods 28 and 280 are adjustably connected to the inner flanges 26 of the channel bars 24 at each end of the unit adjacent to the upper ends of said channel bars and have their lower ends adjustably secured to the flanges 27 of the channel bar 25 adjacent to the top edge of the pan member 14. An additional pair of tension members, as the rods 29 and 31, may also be employed. These rods are adjustably secured at their upper ends to the flanges 27 of the channel member 25 at a point slightly above the bottom portion of the trunk member 13 and their lower ends secured to the inner flanges of the channel

member 24 at points adjacent to the lower portion of the pan member 14. The rods 28, 29 and the rods 280 and 31 cross each other and when the parts are assembled they constitute what might be termed a rigid truss member or unit.

The rods 28, 280, 29 and 31 are most efficient as truss rods if connected to the top of the elevator at one of their ends and to the lower portion thereof at their lower ends, but this arrangement is objectionable because when the rods are tensioned they tend to spread the sides of the trunk member apart. The bottom of the trunk member will prevent the sides from spreading so that by attaching the rods to the trunk sides below the top edge the minimum amount of spreading consistent with proper trussing function is accomplished. In order to further strengthen the construction, the upper edges of the trunk member 13 are bent outwardly and then downwardly to form a reinforcing rectangular bead 32 and the upper edges of the pan member 14 are bent inwardly and downwardly to form similar reinforcing beads 40. It has been found by experiment that a rectangular bead will offer a greater resistance to a bending strain than one in which the material is curved. These beads or reinforcing flanges strengthen the trunk or elevator member and the pan or return member both laterally and vertically.

The channel members 24 are attached to the ends of the unit sections with the outer flanges flush therewith, and when it is desired to connect one unit to another the adjacent flanges of the channel members 24 are connected together as by bolts 33. An additional bolt 34 is also provided for extending thru all the flanges of the channels members at their upper ends. Suitable spacing members or sleeves 35 are inserted between the flanges to hold the same in spaced relation. Connecting strips 36 and 37 are adapted to connect the ends of the units together at their bottom portions as clearly shown in Figs. 1 and 3.

A conventional elevator member comprising the endless chains 38 and drag plates 39 is employed for elevating the grain in the usual manner. The chain and plates are shown more or less diagrammatically in Fig. 3. In order to reduce the wear on the drag plates 39 and chains 38 wooden strips 41 are secured in the corners of the trunk member and extend longitudinally thereof. The chains and plates will be supported by these strips with the plates in close proximity to the bottom wall of the trunk member.

One or more of the elevator units may be perforated as shown at 42 to form grates thru which the shell corn, silks and the like may drop into the pan member and be gathered in baskets or receptacles at the bottom of said pan member. Usually it is only necessary to

provide the lower unit with these grates. A cover is provided for covering the grates when the device is used for elevating small grain.

It is thought from the foregoing taken in connection with the accompanying drawings that the construction and operation of my device will be apparent to those skilled in the art, and that various changes in size, shape, proportion and details of construction may be made without departing from the spirit and scope of the appended claims.

I claim as my invention:

1. In a grain elevator, a sheet metal elevator member, a sheet metal pan member, channel bars connecting said members, said channel bars having their web portions connected to said members, and flanges extending outwardly therefrom, and tension rods extending diagonally across the sides of said elevator and adjustably connected at their ends to the flanges of said channel bars.

2. In combination, a plurality of elevator units each unit comprising a trunk member, a pan member beneath said trunk member, a channel bar at each side of each unit at each end thereof, said bars having flanges extending at right angles to the sides of said members, certain of said flanges being flush with the ends of said members, means for connecting the flanges of adjacent channel bars together for forming a continuous elevator from said units, and tension rods connected to the other flanges of said bars.

3. In combination, a plurality of elevator units, each unit comprising a trunk member U-shape in cross-section, a reinforcing bar secured to each side of each unit at each end thereof and having a laterally extending flange thereon, and means for connecting the flanges at one end of one unit to the flanges at the adjacent end of another unit for holding said units in alinement, and means for connecting each of said flanges to an intermediate portion of the unit to which it is attached for reinforcing said flange and for bracing said unit.

4. An elevator unit comprising a sheet metal trunk member having bottom and side walls, the upper edges of said side walls being bent outwardly and then downwardly to form a reinforcing flange at each side of said trunk member, a pan member below said trunk member and in spaced relation thereto, said pan member having bottom and side walls, the top of said side walls being bent laterally and then downwardly, channel bars for securing said members in spaced relation, said bars being arranged at the ends and intermediate the ends of said members at each side thereof, truss rods arranged at an angle to the axis of said unit and secured to the flanges of said bars, the outer flanges of said bars at the ends of said unit being substantially flush therewith and having open-

ings therein for receiving fastening bolts to connect one unit to another.

5. In combination, a plurality of elevator units, each unit comprising a trunk member, a pan member beneath said trunk member, a plurality of channel bars for securing said members in spaced relation, certain of said channel bars being on the adjacent ends of said units at each side thereof and having 10 abutting flanges, truss rods attached to flanges of said channel bars, bolts for detachably connecting said abutting flanges, bolts extending through all the flanges of the upper ends of said bars at the meeting ends of said units, 15 and spacers on said bolts between the flanges of each bar.

6. In a grain elevator, a sheet metal trunk member having side walls and a bottom wall provided with perforations, a pan member beneath said trunk member, spacer elements for holding said members in spaced relation, said spacer members having outwardly extending flanges, and truss rods adjustably secured to said flanges.

25 7. In a grain elevator, a plurality of elevator units each comprising a trunk member formed from sheet metal and having bottom and side walls, the upper edges of said side walls being bent outwardly at right angles 30 and then downwardly to form strengthening ribs, a pan member beneath each trunk member and coextensive in length therewith, spacers for holding said members in spaced relation, said spacers being provided with flanges, 35 truss members secured to said flanges, the spacers at the meeting ends of said units having abutting flanges, means for securing said flanges together, and strips for connecting the adjacent ends of the bottom walls of said 40 units.

8. In a grain elevator, a sheet metal elevator member U-shape in cross-section and having its upper edges bent laterally at right angles to the side portions of said member 45 and then downwardly parallel with said side portions, a pan member U-shape in cross-section beneath said elevator member and having its side edges bent laterally inwardly substantially at right angles to said side members 50 and then downwardly parallel therewith and spaced therefrom, spacing elements extending transversely of said members and secured thereto, said elements having flanges extending laterally at substantially right angles to 55 said members, and reinforcing rods extending diagonally along the sides of said members and adjustably connected to said flanges.

9. In combination, a plurality of elevator units, each unit comprising a sheet metal 60 trunk member having bottom and side walls, and a pan member U-shape in cross-section beneath said trunk member, bars for connecting said members together and for holding them in spaced relation, said bars being located at the ends and at an intermediate por-

tion of said members and provided with flanges extending at substantially right angles to the sides of said members, means for rigidly connecting said flanges at the ends of adjacent units for connecting said units together, and means including reinforcing rods 70 adjustably connected to said last-named flanges and to the flanges of certain of the intermediate bars for reinforcing the flanges at one end of said unit and for bracing said 75 unit.

In testimony whereof I affix my signature.
JAMES J. DOLAN.
